WHITE WOLF, OF MENLO PARK, CALIFORNIA.

CLOTHES-LINE FIXTURE.

1,176,188.

Specification of Letters Patent. Patented Mar. 21, 1916.

Application filed December 1, 1915. Serial No. 64,431.

To all whom it may concern:

Be it known that I, WHITE WOLF, a citizen of the United States, residing at Menlo Park, in the county of San Mateo and State 5 of California, have invented new and useful Improvements in Clothes-Line Fixtures, of which the following is a specification.

My invention relates to fixtures for supporting clothes-lines and means for adjusting said fixtures with relation to the points 10 between which the clothes-line is to run.

It consists in a pair of endless line-carrying fixtures and their adjustments and a supplemental tension wire with a traveler 15 movable thereon and a hanger depending from the tension wire and adapted to engage the supporting portion of the clothes-line.

It also comprises details of construction 20 which will be more fully explained by reference to the accompanying drawings, in which—

Figure 1 is a side elevation. Fig. 2 is a detailed perspective of the hook suspended 25 from the traveler, and Fig. 3 is a similar view of a modified form of hook for the traveler.

For the purpose of extending clothes-lines between distant points, and particularly in 30 positions which are inaccessible from the ground, it is customary to extend said lines over pulleys located at each end of the space to be covered; these pulleys allowing the line to be moved so as to attach the clothing 35 and afterward to move the line until the whole length has been filled.

My invention is designed as an improvement in this class of apparatus.

As shown in the drawings, A—A' are 40 castings or brackets having right angled extensions B at either end.

2 is a casting which is secured to the fixture A by means of a bolt 3 which passes through lugs 4 on the last mentioned casting 45 and through the extensions B of the fixture A. This casting 2 has horizontally journaled in it a main pulley 5 and an idler pulley 6. The main pulley 5 receives two or more coils of a line 7, which thence passes 50 around the small idler pulley 6 and leads out to the distant point of attachment. At this point is the second fixture A', and attached to it are the lugs 8 of a casting 9. These lugs 8 fit between the extensions B of

the fixture A and are swiveled thereto by 55 means of a bolt 10 which extends through both the upper and lower ends.

Pulleys 11 are journaled at the top and bottom of the casting 9 and substantially register in line with the pulleys 5 and 6 so 60 that the line 7 passes around these pulleys and the first named ones and may thus be caused to move back and forth, so that the line may traverse from one side to the other of the space. The casting 9 is swiveled to 65 turn freely and the fixture or casting 2 has a set-screw, as at 12, passing through one of the lugs 4 and binding against the pin 3 so that when the line is to extend diagonally between points, this fixture may be secured 70 so that the line will extend from it to the distant fixture 9. This fixture 9 is loosely swiveled so that it may take the direction of the line. The fixture 2 is first adjusted in the same direction and is then 75 secured by the set-screw 12.

13 is a crank which may be applied to the end of the shaft of the winding pulley 5, and by turning it, the line may be caused to travel in either direction at will. When 80 these lines are long they are apt to sag, and if heavy goods are applied to them it will be necessary to support them in some way intermediate the ends to prevent this sagging. In my invention I employ a fixture 85 14 which is fixed to the wall or post in line above the fixture A, and opposed to this and in line above the opposite fixture A' is a hook 15 which may be similarly secured.

Journalized in the fixture 14 is a shaft 16, 90 on which is a ratchet 17 and pivoted on the exterior thereof is a dog arranged to drop into the teeth of the ratchet 17 and thus hold it in position. A strong wire 18 has one end fixed to the shaft 16 and the other extends 95 outward and is passed around a hook or support 15. On turning the shaft, as by a handle (not shown), the tension on the wire 18 may be adjusted to any desired degree. One end of the line 7 is fastened to a casting 19 100 which is provided with a clamping bridge 19' over which the opposite end of the line passes. Above this bridge 19' is pivoted a cam 20 having a handle 21 by which it may be lifted out of engagement. When the line 105 has been passed around the hook 15, with the outgoing part lying between the cam and the cam support 19, the cam 20 is forced

down so as to strongly clamp the casting to the line.

Upon wire 18 is a traveler 22 having pulleys which allow it to move freely to any desired point. From this traveler a suspension member 23 extends downwardly and has fixed to it a supporting device for the line 7. This device may be either a simple hook, as at 24, or in the form of tongs 25, 10 between the jaws 26 of which the line could be gripped; the object in any case being to support the line and prevent it from sagging under a heavy load of clothes or when carpets are hung upon such a line.

15 Having thus described my invention, what I claim and desire to secure by Letters Patent is—

1. A clothes-line support consisting of a fixture having a main winding pulley and 20 an idler, and a distant fixture carrying two idlers journaled in line with the first named pulleys, around which pulleys and idlers an endless rope is extended, the first named fixture having means by which it may be secured in the desired line of travel of the rope, 25 and the second fixture being loosely swiveled

and freely turnable to take the same direction.

2. The combination in a clothes-line support, of fixtures at opposite ends of the space, 30 said fixtures being swiveled and turnable to align with each other, and one of said fixtures having means for securing it rigidly in position, pulleys journaled at the top and bottom of said fixtures, an endless line passing around said pulleys, one of which serves as a motor to move the line.

3. A clothes-line support comprising a bracket, a pivot bolt thereon, a frame having an apertured lug receiving the bolt for 40 swinging thereon, means carried by the lug for securing the same fixed to the bolt, a pulley journaled on the frame, a distant fixture, and an endless line taking over the pulley and distant fixture.

45 In testimony whereof I have hereunto set my hand in the presence of two subscribing witnesses.

WHITE WOLF.
